SNAP ACTION SWITCH

Lawrence M. Persons, Chesterfield, Mo., assignor
to McQuay-Norris Manufacturing Company,
St. Louis, Mo., a corporation of Delaware

Application May 15, 1947, Serial No. 748,222

8 Claims. (Cl. 200—83)

1

This invention relates generally to electrical control apparatus and particularly to a snap action switch.

While snap action switches have heretofore been provided in a variety of forms, the devices of the character heretofore known have not only been difficult and tedious to manufacture, but have required a substantial movement of an actuating member in order to initiate the movement of the switch parts from one position to another.

The object of the present invention, generally stated, is to provide a snap action switch, which is not only economical to manufacture and easy to assemble, but which is actuated from one position to another in response to very slight movements of an actuating member.

Other objects will become apparent to those skilled in the art when the following description is read in connection with the accompanying drawings, in which:

Figure 1 is a view in side elevation (the enclosing case being shown in section) of a snap action switch constructed in accordance with the present invention;

Figure 2 is a sectional view taken along line 2—2 of Figure 1; and

Figures 3, 4, 5, and 6 are a series of diagrammatic views illustrating the several positions of the cooperating parts of the switch shown in Figure 1.

In accordance with the present invention, a snap action or toggle type switch is produced and the contact member maintained in position solely through the office of an over-center spring, whose force is exerted in a direction such as to maintain the contact member seated upon a knife-edge pivot. Consequently, the contact member may be readily dismounted from the organization by relief of the spring tension thereon. A further important feature of the invention is to provide in the organization of contact members and actuating members an arrangement whereby the contact member is positively moved upon failure of the impositive spring connections to move the same, as sometimes results when the contacts stick.

Referring now to the drawings for an illustrative embodiment of the invention, a contact member 1 is provided with a knife-edge bearing 2 seated upon a bracket 3 carried by an insulation base 4.

In the form shown, the contact member 1 is provided with a pair of movable bridging contacts 5 arranged for selective engagement with a set of stationary contacts 6 or a set of stationary

2

contacts 7, in accordance with the position thereof.

In order to hold the contact member 1 seated upon the bracket 3, a thrust link 8 having a tongue 9 projecting through a lip 10 of the contact member 1 is provided. The other end of the link 8 is engaged by a leaf spring 11 stressed so as to urge the contact member 1 continuously in the direction which maintains the knife-edge 2 seated upon the bracket 3. The connection between the link 8 and the spring 11 is similar to the connection between the link and the contact member 1 consisting of a tongue 12 extending through an orifice in the leaf spring 11.

The spring 11 is mounted for movement in a vertical direction, as shown in Figure 1. In the embodiment shown, the mounting for the spring 11 consists of a piece of insulating material 120 connected to the extremity of a lever 13, which latter is pivoted on a shaft 14. Within the confines of the adjunct structure, the spring 11 is, therefore, movable about shaft 14 as an axis.

The actuating force to initiate movement of lever 13 and spring 11 about axis 14 is applied, in the embodiment illustrated, through an operating lever 15 pivoted on shaft 16.

The end of lever 15 most remote from its point of pivot is arranged to engage a boss 17 on lever 13 closely adjacent the pivot-axis of the latter. Intermediate the ends of operating lever 15, a pressure member 18 is arranged to bear. In the embodiment illustrated, the pressure member 18 is associated with a bellows and actuated by fluid pressure, but it will be understood that any convenient arrangement may be employed for applying an actuating force to lever 15. With the arrangement of parts shown, it will be apparent that a very slight movement of the pressure member in a vertical direction results in a very considerable movement of the spring 11 in a vertical direction due to the arrangement of fulcrums and hence the multiplying action of the levers 15 and 13.

In order to cause the levers 13 and 15, and hence the contacts, to follow recession of the pressure member 18, a pair of spring 19 and 20 are mounted to exert a force upon the lever 13 tending to rotate the same in a counterclockwise direction about its pivot 14. The provision of two springs, as shown, facilitates calibration of the switch within very narrow limits of tolerance, a rough calibration being accomplished by adjustment of a relatively heavy spring 19 arranged to exert its force through a relatively short moment arm and the fine calibration being accomplished

by appropriate adjustment of a relatively weak spring 20 arranged to exert its force through a greater moment arm.

If it be desired to provide the switch with a mechanism for positively moving the contact member 1 in the event that the contacts should stick and the impositive connections through spring 11 and link 8 be incapable of moving the contacts, the contact member 1 may have an extension 21 beyond the knife-edge 2. The extremity of the extension 21 is embraced by a stirrup 22, but these parts are normally not in physical engagement one with the other. As shown in the drawings, the stirrup 22 is mounted upon an insulation plate 23 fixed to lever 13 so that the stirrup moves in a vertical direction as the lever 13 rocks about its pivot 14. When, in the event the contacts have stuck, the spring 11 yields and does not accomplish a movement of the contact member in response to movement of lever 13, one side or the other of stirrup 22 will come into engagement with the extension 21 of contact member 1 and directly transmit a force from lever 13 thereto, positively moving the same. It will be understood, of course, that, in situations where such sticking of the contacts is not likely to occur, the extension 21 and the stirrup 22 may be omitted.

An understanding of the operation and advantages of the structure will be clear from a consideration of Figures 3 to 6, inclusive, wherein the several parts are diagrammatically shown. In Figure 3, the contact member 1 is at one extreme position wherein the movable contact 5 is engaging the stationary contact 7. When in this position, the force exerted by spring 11 through link 8 tends to maintain the knife-edge 2 seated, but the direction of the force imparted to contact member 1 through link 8 is such as to bias the contact member in a clockwise direction about its fulcrum at 2. If, now, a force be exerted such as to rock lever 13 about its pivot 14, the spring 11 moves upwardly to the position shown in Figure 4 wherein it will be observed that the direction in which the force of spring 11 is imparted through link 8 to contact member 1 passes through the fulcrum 2, as shown by the broken line, but at this time the contacts 5 are still in engagement with the upper stationary contact 7. Any slight movement beyond the position shown in Figure 4 causes the line of force from spring 11 to contact member 1 to pass on the lower side of the fulcrum at 2 and consequently swings the contact member into the position shown in Figure 5 where the movable contacts 5 engage stationary contacts 6. In the event, however, that the movable contact 5 has stuck in engagement with the stationary contact 7, the contact member 1 may remain in the position shown in Figure 4 even after the position of link 8 has shifted so that the line of force is below the fulcrum at 2. Such condition is represented in Figure 6 where it will be observed that, although the line of force from spring 11 is in a direction tending to rotate the contact member 1 in the counterclockwise direction (which would separate movable contact 5 from stationary contact 7), the parts have not so moved. At this point, however, the extension 21 of contact member 1 has been engaged by the lower lip of stirrup 22 so that any further slight movement of lever 13 in the clockwise direction about its axis 14 will apply a direct force to the extension 21 of contact member 1 and result in breaking the stuck contacts 5 and 7. It will be observed

that, at the stage illustrated in Figure 6, the force of spring 11 tends to assist the breaking of the contacts 5 and 7 and consequently, when the stirrup 22 has applied sufficient force to break the frozen connection, the force of spring 11 comes into play to immediately snap the contact member to its opposite position, as shown in Figure 5. If movable contact 5 should freeze to stationary contact 6, the operation of the parts is in the reverse order. In this instance, the upper lip of stirrup 22 engages extension 21 to free the contact member 1 for movement in a clockwise direction about its fulcrum 2 under the influence of spring 11.

From the construction and organization of the parts, as above described, it will be apparent that, if it be desired to replace contact member 1, all that is necessary is to bias spring 11 leftwardly until link 8 is released either from the spring or lip 10 of contact member 1 whereupon the contact member may be lifted out of position without necessitating the removal of any shafts or other balancing devices. This aspect of the invention is important not only from the standpoint of replaceability of the contact member, but also in that it greatly facilitates the initial formation and assembly of the parts.

From the foregoing description, those skilled in the art should readily understand the operation and advantages of the switch. While one complete embodiment has been described in detail, it is not intended that the invention be considered as limited to the details of that disclosure, but, on the contrary, it is realized that many modifications will suggest themselves to those skilled in the art without departing from the spirit of the invention or the scope of the appended claims.

Having thus described the invention, what is claimed and desired to be secured by Letters Patent is:

1. A pressure switch comprising a contact carrier movable between two positions, means for imparting moving force to said carrier, said means including a spring continuously biasing the carrier in a direction substantially perpendicular to the direction of movement of said carrier, a thrust link interconnecting said spring and said carrier, said spring being movable in a direction substantially parallel to the direction of movement of said contact carrier to actuate the latter, and a lost motion connection between said means and said carrier to limit movement of the former relative to a given position of the latter.
2. A pressure switch comprising a contact carrier movable between two positions, means for imparting moving force to said carrier, said means including a spring continuously biasing the carrier in a direction substantially perpendicular to the direction of movement of said carrier, a thrust link interconnecting said spring and said carrier, said spring being movable in a direction substantially parallel to the direction of movement of said contact carrier to actuate the latter, and said means also including a member having a non-yielding part normally out of engagement with said carrier but disposed to engage said carrier and impart moving force thereto when said spring moves without moving said carrier.
3. A pressure switch having a contact carrier movable between two positions about a fulcrum, a knife-edge mounting providing the fulcrum for said carrier, a movable spring continuously biasing said carrier in the direction to maintain seating of the knife-edge pivot, the connection

between said spring and said carrier and the connection between said carrier and said mounting being freely separable upon movement in the direction opposed by the force of said spring, and means for changing the direction of the moment of the spring upon the carrier to move the latter between said two positions.

4. A pressure switch having a contact carrier movable between two positions about a fulcrum, a knife-edge mounting providing the fulcrum for said carrier, a thrust link engaging a part of said carrier remote from its fulcrum, and a movable spring urging said link into engagement with said carrier and said carrier into seating relation at said knife-edge pivot, the connections between said spring said link and said carrier, as well as the connections between said carrier and said mounting, being freely separable upon movement in the direction opposed by the force of said spring.

5. A pressure switch having a contact carrier movable between two positions about a fulcrum, a knife-edge mounting providing the fulcrum for said carrier, a thrust link engaging a part of said carrier remote from its fulcrum, a movable spring urging said link into engagement with said carrier and said carrier into seating relation at said knife-edge pivot, said spring being the only means preventing displacement of said carrier from said mounting, and a movement-multiplying lever supporting said spring.

6. A pressure switch having a contact carrier movable between two positions about a fulcrum, an operating lever pivoted at one end, an actuator engaging said lever closely adjacent the pivoted end, a spring mounted on said lever at the opposite end thereof, the pivot for said lever and the fulcrum for said contact carrier lying in substantially parallel planes and said spring being tensioned to exert its force in a direction substantially parallel with the planes thereof, and a link transmitting the force of said spring to said carrier and arranged to reverse the moment thereof during movement of said lever.

7. A pressure switch having a contact carrier movable between two positions about a fulcrum,

an operating lever pivoted at one end, an actuator engaging said lever closely adjacent the pivoted end, a spring mounted on said lever at the opposite end thereof, the pivot for said lever and the fulcrum for said carrier lying in substantially parallel planes and said spring being tensioned to exert its force in a direction substantially parallel with the planes thereof, a link transmitting the force of said spring to said carrier and arranged to reverse the moment thereof during movement of said lever, and a part movable with said lever embracing but normally not engaging said carrier on the opposite side of the fulcrum thereof from said link.

15 8. A pressure switch having a contact carrier movable between two positions about a fulcrum, an operating lever pivoted at one end, a spring mounted on said lever at the opposite end thereof, the pivot for said lever and the fulcrum for said carrier lying in substantially parallel planes and said spring being tensioned to exert its force in a direction substantially parallel with the planes thereof, a link transmitting the force of said spring to said carrier and arranged to reverse the moment thereof during movement of said lever, an actuating lever pivoted remote from the pivot of the operating lever but engaging the latter adjacent its pivot point, and means for applying a force to the actuating lever between its pivot and its point of engagement with said operating lever.
